UNITED STATES PATENT OFFICE

FRANK L. MOORE, OF CHATHAM, NEW JERSEY

SAFETY DEVICE FOR ELEVATORS

Application filed January 25, 1929. Serial No. 334,899.

This invention relates to improvements in safety devices for elevators, and more particularly to a device or mechanism which will be placed at every floor in an elevator shaft to cooperate with spaced cams on the elevator car to positively prevent the operation of the car when the door in the shaft is open.

Among the principal objects of my invention are as follows: To prevent the accidental or intentional operation of an elevator car while the door to the shaft is open at the floor where the car is stopped; to positively and automatically close any door accidentally left open in the shaft, as the car moves up or down the shaft; and to provide an improved safety device for self-operated elevators which will swing out into the path of movement of the elevator car to support its weight should the cables break or the car slip. Other objects will appear as the description proceeds.

Drawings

25 Figure 1 is a front elevation of a portion of an elevator shaft and door therefor equipped with my improved device;

Figure 2 is a side elevation of my safety apparatus showing the elevator shaft, door 30 and car in section;

Figure 3 is a plan view of my safety apparatus showing the elevator shaft, door and car in section;

Figure 4 is a perspective view of my improved safety apparatus;

Figure 5 is a front elevation of the apparatus;

Figure 6 is a plan view showing the cam in engagement with the face of the safety rudder and showing various positions of the rudder in dotted lines.

Description

In carrying out my invention, I provide 45 an operating bar 1, which is slidably mounted in the slotted brackets 2 above each door opening in an elevator shaft, and extending transversely of the opening. Each bar 1 is formed with the spaced stop shoulders 50 3 at one end thereof, arranged at the opposite

sides of one of the brackets 2 and serves to limit the sliding movement of the rod. These shoulders may be positioned at any place on the bar or on the wall of the shaft. A heavy rudder plate 4 is pivotally supported in vertical position between the bearing sockets 5 adjacent one side of each door opening in the elevator shaft 6 and is adapted to be swung into the shaft in the path of the elevator car or to be swung back 55 against the wall of the shaft by a linkage connection with the sliding bar 1 when the car door is respectively opened and closed. The connection between the plate 4 and the rod 1 includes a pin 8 carried on a laterally 60 extending arm 9 on the plate 4 which is loosely received in the slot 10 between the spaced ears 11 formed adjacent the end of the rod 1 opposite the shoulders 3.

Intermediate the ends of the rod 1 is 70 a cam plate 12 pivoted at 13 to the said rod 1, and has its outer end tapered and extending through a slot 14 in the fixed arm or bracket 15. A shoulder 16 is also formed on the lower side of the plate 12 intermediate 75 its ends and is adapted to engage an operating pin 17 carried by the bracket 18 on the door 19 to the shaft 6, while a second shoulder 20 on the lower side of the bar 1 engages the other side of the said pin. If it is desired to use the rod 1, without the cam plate 12, a shoulder 21 spaced from the shoulder 20 will be employed so that when the pin is engaged by either shoulder, the rod 1 will be shifted from side to side.

Cam brackets 23 and 24 are secured respectively to the upper and lower side edges of the car 7 and are adapted to contact with the rudder plate 4 if the same is extended out into the elevator shaft, to force the said 90 plate inwardly parallel with the wall of the shaft. Each bracket is also provided with an auxiliary cam surface 25 which engages the plate after the main cam surface has started to swing the plate, thereby positively 95 forcing the plate into retracted position.

From the foregoing description, the mode of operation will be understood to be as follows: Assuming that the elevator car is 100 on the level of a floor and the shaft door is

closed, the several parts will assume the relative position shown in Fig. 1 of the drawings. As the door is drawn open, the pin 17 carried by the door, will be released from the shoulder 16 as the plate raises on its cam surface, thereby permitting the door to open fully. If a door below or above the car is opened and left open, the rudder at that floor will be extended into the shaft so that when the car descends or ascends, the cam at the bottom or top of the car will engage the rudder and swing it into parallel relation with the wall, thereby removing the same from the path of the elevator car.

15 During the period when the elevator door is open, the rudder 4 is swung outward between the brackets 26-26, thereby locking the elevator in the receiving position. As the door is closed, the rudder 4 is moved out of engagement with the said brackets 20 permitting the car to descend or ascend.

It will be understood that many minor changes in detail of construction may be resorted to without departure from the spirit of the invention.

25 **Claims:**

1. An elevator safety device in combination with an elevator car and shaft therefor having a plurality of door openings, an operating bar mounted transversely of a door opening, a rudder plate mounted to be swung into said shaft and operatively connected with said bar, a cam plate carried by said bar, and means carried by the car for operatively engaging said rudder plate.

2. An elevator safety device in combination with an elevator car and shaft therefor having a plurality of door openings, a rudder plate mounted at the side of each door opening in said shaft, means on each door operatively connected to said rudder plates to cause the same to swing out into the shaft when a door is opened, and plural cams arranged at an angle to each other arranged at the top and bottom of said car for engaging an outwardly directed rudder plate as the car ascends or descends to force the plate out of the path of the car and against the wall of the shaft.

50 3. An elevator safety device in combination with an elevator car and shaft having a plurality of door openings, including an operating bar mounted transversely of each door opening, means for limiting the transverse movement of said bar, a rudder plate mounted at the side of each door opening and being operatively connected with said bar, a slotted bracket adjacent each of said bars, a cam plate pivotally supported on each bar adapted to extend through said slotted brackets, and shoulders formed on said bars and cam plates adapted to cooperate with means carried by the doors in the 60 shaft to positively cause the rudder plates to

swing out into the shaft when a door is opened.

4. An elevator safety device in combination with an elevator car and shaft having a plurality of door openings, including an operating bar mounted transversely of each door opening, means for limiting the transverse movement of said bar, a rudder plate mounted at the side of each door opening and being operatively connected with said bar, a slotted bracket adjacent each of said bars, a cam plate pivotally supported on each bar adapted to extend through said slotted brackets, shoulders formed on said bars and cam plates adapted to cooperate with means carried by the doors in the shaft to positively cause the rudder plates to swing out into the shaft when a door is opened, and means on the elevator car for engaging a rudder plate extending into the shaft as the car ascends or descends to force the same out of the path of the car and against the wall of the shaft.

5. An elevator safety device in combination with an elevator car and shaft having a plurality of door openings, including an operating bar mounted transversely of each door opening, means for limiting the transverse movement of said bar, a rudder plate mounted at the side of each door opening and being operatively connected with said bar, a slotted bracket adjacent each of said bars, a cam plate pivotally supported on each bar adapted to extend through said slotted brackets, and cams mounted at the top and bottom of said car for engaging the rudder plate as the car ascends or descends to force the plate out of the path of the car and against the wall of the shaft.

6. An elevator safety device in combination with an elevator car and shaft having a plurality of door openings, including an operating bar mounted transversely of each door opening, means for limiting the transverse movement of said bar, a rudder plate mounted at the side of each door opening and being operatively connected with said bar, a slotted bracket adjacent each of said bars, a cam plate pivotally supported on each bar adapted to extend through said slotted brackets, and plural angularly arranged cams at the top and bottom of said car for engaging the rudder plate as the car ascends or descends to force the rudder plate out of the path of a passing car and against the wall of the shaft.

7. An elevator safety device in combination with an elevator car and shaft having a plurality of door openings, including an operating bar mounted transversely of each door opening, means for limiting the transverse movement of said bar, a rudder plate mounted at the side of each door opening and being operatively connected with said bar, a slotted bracket adjacent each of said bars, a cam plate pivotally supported on each bar adapted to extend through said slotted brackets, and shoulders formed on said bars and cam plates adapted to cooperate with means carried by the doors in the 125 shaft to positively cause the rudder plates to

bars, a cam plate pivotally supported on each bar adapted to extend through said slotted brackets, shoulders formed on said bars and cam plates adapted to cooperate with means carried by the doors in the shaft 5 to positively cause the rudder plates to swing out into the shaft when a door is opened, and spaced ledges carried by the elevator adapted to bracket said rudder plate between the same for locking the elevator in fixed position while the door stands open.
